UNITED STATES PATENT OFFICE.

BERNARD H. KERSTING, OF BEN AVON, AND VERE B. EDWARDS, OF CORAOPOLIS, PENNSYLVANIA, ASSIGNORS TO THE DRAVO CONTRACTING COMPANY, OF PITTSBURGH, PENNSYLVANIA, A CORPORATION OF PENNSYLVANIA.

ROAD-BUILDING FORM.

Application filed May 7, 1925. Serial No. 28,626.

To all whom it may concern:

Be it known that we, BERNARD H. KERSTING and VERE B. EDWARDS, residing at Ben Avon and Coraopolis, respectively, in the county of Allegheny and State of Pennsylvania, citizens of the United States, have invented or discovered certain new and useful Improvements in Road-Building Forms, of which improvements the following is a specification.

Our invention concerns forms for road-building. While the material of which the road is built is not a limitation of the field of our invention, we have developed it as a form for building concrete roads, and we shall in the ensuing specification describe it in use in building concrete roads. Forms of the general sort, upon which we have made improvement, are adapted to be erected temporarily in parallelism, along either side of the roadway under construction, and when in place to serve as the limiting walls in the spread of paving material and to serve also as rails upon which the spreading and finishing apparatus may travel. The forms are made of lengths of sheet steel, of properly shaped and proportioned cross-section, and the lengths are fitted and secured together, end to end. When the forms have served the uses described, and when the pavement spread and shaped between them has hardened, the forms are removed. The fact that they are made up in lengths fitted together facilitates removal, and also makes possible a progressive laying, so that from end to end of a strip of road, the forms will never be entirely removed, but will extend farther and farther, by the addition of fresh lengths as work advances. To rearward the lengths will be removed, as road-building progresses. The objects of our invention are facility of installation and removal and firmness in service.

In the accompanying drawings Fig. I is a plan view from above of the connected ends of two lengths of our improved form, as the structure appears when in service position. Fig. II is a view in side elevation of the same assembly. Fig. III is a horizontal section, on the plane indicated by the line III-III, Fig. II. Fig. IV is a view in transverse and vertical section, on the plane indicated at IV-IV, Fig. II. Figs. V and VI are views corresponding to Figs. I and

II, but showing the two form lengths separated and standing apart, one from the other. Figs. VII and VIII are views in transverse and vertical section, on the planes indicated at VII-VII and VIII-VIII, respectively, in Fig. VI.

A length of the form of our invention is conveniently made from a rolled sheet or plate of steel, fashioned into the cross section sufficiently shown in Figs. IV, VII, and VIII, and including a median web 1, which when the form is in place serves as the retaining wall for the wet concrete, a flange 2 which serves as a base, and a flange 3 which serves as a head. The structure is adapted to stand upon its base 2 and to afford by its head 3 a track upon which the road-spreading and finishing instrumentalities may travel. The edge of flange 3 is downturned, as appears at 4.

It is the left-hand face of the structure as seen in Fig. IV against which the concrete is spread.

On the opposite side of the steel shape, and within the channel formed with the web 1 by the flanges 2 and 3, stake-boxes are secured at proper intervals. As hereinafter will appear there is preferably a stake-box immediately adjacent one end of each form length, and there will be one or more additional stake boxes secured at suitable intervals therefrom.

The stake-box of our invention is cut from steel plate, shaped and riveted to place. Its vertical walls 5 are flanged along the inner and lower edges and riveted to the web 1 and to the base flange 2. The upper wall 6 of the box forms a sloping roof, and extends from the channel web beyond the downturned edge 4 of head 3. In the opposite side walls 5 of the stake-box opposite pairs of openings 7, 7 and 8, 8 are formed; and in the upper wall 6 and in the base flange 2 opposite openings 9 and 10 are formed.

The opening 10 is of suitable size to allow free passage of a stake 11, and opening 9 is of such shape and size that the introduced stake fits snug within it. The stake is preferably square in cross section, and the opening 9 is correspondingly rectangular.

A wedge 12 slides in the openings 7, and the openings 7 are so particularly placed that when the form is assembled with the stake, the driving home (left to right, Fig.

I) of wedge 12 will insure the gripping of the stake between the wedge surface and the opposite and lower edge of opening 9 in the upper wall 6 of the stake-box. The wedge 5 is conveniently made of steel sheet or plate cut and bent to shape. It is channel-shaped in cross-section, and, by virtue of this particular shape, conjointly with the square shape of the stake and the rectangular shape 10 of opening 9, the engaging surfaces and edges are extended, and the wedging engagement is made more secure.

By means of the parts thus far described the form length is secured to the stake, and 15 the form may be raised and hung to the stake at any desired point of elevation. This feature is known to the art, but the refinements described for making more secure connection are new.

20 As has been said, the opening 9 snugly fits the stake 11, and the upper wall 6 of the stake-box is sloped. These features have utility in that ingress of concrete into the stake-box is well guarded against, and the 25 stake-box tends to shed wet concrete which may accidentally fall upon it. It will be observed of the side walls 5 of the stake-box that they are cut away at their inner corners 13, to facilitate the removal of concrete 30 which may accidentally find lodgment within, as well as of other accumulations. The whole structure is strong to endure service conditions. The stake-box becomes a bracket, bracing the web and bottom flange 35 of the channel.

We have said of the stake-box that through opposite walls it is provided with 40 openings 8, 8. These have to do with the union of successive lengths of the form in end-to-end articulation. And it is those 45 stake-boxes only which are arranged immediately adjacent the end of the length which need be provided with these openings. Other more remote stake-boxes may lack the openings 8, 8.

The top flanges 3 are cut with oppositely off-set edges, preferably obliquely inclined, as will be seen best in Fig. V. On one end of each length (the right-hand end, as seen 50 in Fig. V) the top flange 3 with its depending edge 4 projects beyond web 1 and base flange 2; at the other end (the left-hand end) the flanges 3, 4 are correspondingly cut away. By this particular provision it 55 will be perceived that two lengths may be brought together by transverse shifting, and that as one length (the length to the left, Fig. I) is moved upward (as viewed in the drawing), relatively to the 60 companion length, the obliquely disposed edges *a*, *b* of flanges 3 come to bearing one on another, and resist further movement. It will be perceived also that by virtue of the 65 oblique arrangement of the meeting edges of the flange 3, a continuous support is af-

fording for a vehicle wheel running upon the form.

It is the left-hand end of the length which in this case carries the stake-box already described. The opposite end, the right-hand end of the length carries a plate 14. This plate is of proper size and shape to be brought to the position shown in Fig. VII, and riveted to place. It lies closely upon web 1 and within flanges 3 and 4. Its lower margin is inclined somewhat, and meets and is riveted to the base flange 2 near the outer edge of flange 2 and beyond the vertical prolongation of the plane of flange 4. At its heel the plate 14 stands away from the corner formed by and between web 1 and base flange 2, as is indicated at *s*. The mid-web of plate 14 extends beyond its upper and lower flanges in a tongue 15. The plate 14 throughout all its extent projects from the end of the form length by as much as the flanges 3 and 4 extend, and the tongue 15 extends to still greater distance. By virtue of this particular construction, it matters not whether the progress of uniting successive form lengths end to end be in one direction or the other. The structure described affords support, the already placed section sustaining the newly applied section at the proper elevation and in proper position. When the adjacent lengths are by transverse movement fitted together, the tongue 15 of one part abutting against the mid-web 1 of the other, will (additionally to the engagement of edges *a* and *b*) resist further movement and effect accurate alignment. Upon the face of plate 14, and riveted to place with it upon the web 1 of the form length lies a reinforcing bar 16. It may not protrude as far as does the tongue 15. It serves 105 to resist and distribute wedge pressure.

The stake-box adjacent the end of the form length carries in its openings 8, 8 a wedge 17, similar in structure to wedge 12 already described, and when two lengths of form have been brought together, to the position shown in Figs. I-III, the wedge 17 is shifted from right to left, and it serves to clamp bar 16 and plate 14 upon the web 1 of the form length which carries the stake-box. Thus the form lengths are secured in accurately aligned position. It is a matter of great advantage that by the particular means shown the form lengths may be brought together and separated by transverse movement, and do not require longitudinal telescopic movement, as is usual.

We claim as our invention:

1. A form for road building including a channel-shaped member adapted to stand with its medial web presented in vertical position to the work, said channel-shaped member carrying within the channel a stake-box with inclined and ported upper wall, and a wedge borne by and movable in its 125

bearing in the stake-box, arranged opposite the lower rim of the port in the said upper wall and adapted to cooperate with the opposite rim of the port in gripping an introduced stake.

2. A form for road building including a channel-shaped member adapted to stand with its medial web presented in vertical position to the work, said channel-shaped member carrying within the channel a stake-box with inclined upper wall provided with a rectangular orifice, and a wedge formed of sheet steel of channel-shaped cross-section borne by said stake-box and shiftable in the direction of the length of the structure and adjacent the higher side of said port and adapted to cooperate with the opposite and lower rim of the port, and to clamp against such opposite rim a stake with opposite parallel sides.

3. A form for road building including two channel-shaped members adapted to stand with their medial webs presented in vertical position to the work, one member being provided with a tongue extending from its web portion at one end and adapted when the two members are brought together, to overlie the web of the other member, and a stake-box borne by the other member and carrying a movable wedge adapted to clamp the tongue of the member first mentioned against the web of the second member.

4. A form for road building including two channel-shaped members adapted to stand with their medial webs presented in vertical position to the work, one of said members bearing within the channel a flanged plate spaced from the inner face of the member which carries it along the inner portion of the base flange but elsewhere lying closely upon the inner surface of such member, said flange plate extending beyond the end of the member which carries it and

adapted to overlie the inner face of the other of the two channel-shaped members, a wedge movably borne by such other member and adapted to clamp the plate of the member first named against the web of the member which carries the wedge.

5. A form for road building including two channel-shaped members adapted to stand with their medial webs presented in vertical position to the work, the upper flanges of adjacent ends of said members presenting each to the other oppositely offset edges, and means borne by one for clamping the other to itself with said oppositely off-set edges in engagement.

6. A form for road building including two channel-shaped members adapted to stand with their medial webs presented in vertical position to the work, the upper flanges of adjacent ends of said members presenting each to the other oppositely off-set edges, one of said members provided with a projecting tongue adapted to overlie the medial web of the other member and such other member carrying movable means for clamping the overlying tongue to itself, the oppositely off-set edges of the upper flanges being in engagement.

7. A form for road building including two channel-shaped members adapted to stand with their medial webs presented in vertical position to the work, the upper flanges of adjacent ends of said members presenting each to the other opposite obliquely disposed edges, whereby when two lengths are assembled the so made up form afford continuous support for the wheel of a vehicle traveling on the form.

In testimony whereof we have hereunto set our hands.

BERNARD H. KERSTING.
VERE B. EDWARDS.
